COMBINED HOLDER AND THERMO INSULATOR FOR A BABY NURSING BOTTLE

Anthony Sepe and Louis J. Sepe, both of
2403 Hubbard St., Brooklyn, N.Y.

Filed July 7, 1959, Ser. No. 56,691

Term of patent 3½ years

(Cl. D83—8)

Fig. 1 is a front elevational view of a combined holder and thermo insulator for a baby nursing bottle, showing our new design;

Fig. 2 is a rear elevational view thereof;

Figure 3 is a right side elevational view thereof;

Fig. 4 is a sectional view taken on the line 4—4 of Fig. 2; and

Fig. 5 is a top plan view thereof.

We claim:

The ornamental design for a combined holder and thermo insulator for a baby nursing bottle, substantially as shown.
